REFRIGERATOR CABINET HAVING
ICE-CREAM CAN SUPPORT MEANS

Harry W. Custer, Center Line, Mich.

Application October 13, 1944, Serial No. 558,510

1. Claim. (Cl. 62—89)

1

This invention relates to ice cream cabinet and has for one of its objects the production of a simple and efficient cabinet having a downwardly inclined or angular well within which the ice cream can may rest so that the contents of the can will be easily accessible and the ice cream may be easily removed from the can without requiring the attendant to dip into the can with a direct downward motion.

Another object of this invention is the production of a simple and efficient ice cream cabinet or other freezing or cooling unit having an angularly extending well inclined in a downward direction at its inner end and means for supporting a can within the well.

Other objects and advantages of the present invention will appear throughout the following specification and claim.

In the drawing:

Figure 1 is an end elevational view of the cabinet;

Figure 2 is a front elevational view of the cabinet;

Figure 3 is a vertical sectional view through the cabinet and through one of the inclined wells;

Figure 4 is a perspective view of the can-supporting rack;

Figure 5 is a front elevational view of the can-supporting rack;

Figure 6 is a vertical sectional view through the rack looking toward the rear end thereof; and

Figure 7 is a fragmentary side elevational view of the rack illustrating the rear end of the rack and the manner in which the can abuts the inner end of the rack.

By referring to the drawing, it will be seen that 10 designates the cabinet which may be of suitable design but which is preferably provided with a front wall which is inclined from the central front portion toward the top as indicated at 11, and is inclined from the central front portion toward the bottom, as indicated at 12. A suitable freezing unit 13 indicated in dotted lines in Figure 3, is preferably mounted in the bottom of the cabinet 10 and an angular freezing well 14 is carried by the top of the cabinet, the freezing well 14 being inclined downwardly from the front opening 15 toward the rear end 16, as shown in detail in Figure 3. A suitable closure cover 17 is hingedly secured to the cabinet 10 above each well 14 to provide an efficient sealing closure as is usual with ice cream cabinets and other freezing units.

It should be understood that any suitable num-

ber of wells may be employed or mounted within the cabinet 10 and these wells may be arranged in any suitable or desired manner without departing from the spirit of the invention. The improved feature of the invention, however, is the fact that the well 14 is an angular well at an incline downwardly from the entrance opening in the upper front portion of the cabinet and extends downwardly toward the rear and lower portion of the cabinet, as shown in Figure 3.

As shown in Figures 4 to 7 inclusive, I employ a special rack which is preferably formed of a strand of suitable material such as wire, steel bar material, and the like, and this rack 15 comprises a pair of parallel side members 18, which side members 18 terminate at their forward ends in a downwardly extending right-angularly arranged U-shaped loop 19. The opposite or rear ends of the side members 18 terminate in upwardly extending members 20, the upper ends of which are formed into forwardly bowed loop portions 21 projecting forwardly of the upwardly extending members 20. These loops extend parallel to the side members 18 and the extremities 20 of the loop portions 21 are bent downwardly to form a depending U-shaped loop 22. These loop portions 19 and 22 support the parallel side members 18 above the bottom face 23 of the angular well 14, as shown in Figures 3 and 7 when the rack is mounted in position.

The ice cream can 24 is placed longitudinally of the rack in the position shown in dotted lines in Figures 3 to 6 inclusive, and in full lines in Figure 7. The can 24 lies or rests upon the parallel side members 18 and a portion of the can which is of a cylindrical formation will lie down between the parallel side members 18 in the manner shown in Figure 6, thereby holding the can against lateral displacement within the well 14 and the rear end 25 of the can 24 will abut against the forwardly bowed loop portions 21 and will be supported against a minimum resistance or contact surface at its rear end. Because of the 40 particular construction of the rack, it will be noted that the can will be supported in a manner whereby a minimum contact surface is in engagement with the can thereby facilitating the removal or detachment of the can from the 45 rack with a minimum effort in view of the fact that a minimum contact surface is provided upon the rack which would be likely to freeze solidly to the can or container.

The rack above described may be made of 50 steel bar material of a suitable strength to sup-

port the cans 24 which rest thereon. Furthermore, the present structure is adaptable for use in cabinets of any type, such as freezing, cooling, or other units, without departing from the spirit of the invention.

It should be understood that various types of containers might be employed for various arrangements upon the wells, and the wells may be arranged as shown in Figure 2, or may be arranged in staggered relation as is common in such types of cabinets without departing from the spirit of the invention. The cabinet may be so constructed as to support a plurality of wells in any selected arrangement so long as these wells are angularly mounted to incline downwardly and inwardly of the cabinet from the outer open end of the cabinet.

Certain detail changes in the construction may be employed without departing from the spirit of the invention so long as such changes fall within the scope of the appended claim.

Having described the invention, what I claim is:

In combination with a refrigerating cabinet having an angular well inclined downwardly toward its inner end and having an inner end wall, top wall, bottom wall and side walls, a removable rack having rounded contacting surfaces engaging the bottom and end walls of the well, the rack

having side rails for slidably supporting a tubular receptacle away from the bottom wall to facilitate the insertion of and removal of the receptacle into and out of the well, the side rails having 5 rounded receptacle engaging surfaces, the rack having abutment elements at the inner end for engaging the inner end of a receptacle to support the inner end of the receptacle in spaced relation from the end wall of the well, and the abutment elements having rounded abutment areas 10 for contact with the inner end of the receptacles.
